UNITED STATES PATENT OFFICE.

WENDELL E. HERBST, OF HARTFORD, CONNECTICUT.

RUBBER TREAD.

No. 897,860.

Specification of Letters Patent. Patented Sept. 1, 1908.

Application filed November 8, 1901. Serial No. 81,602.

To all whom it may concern:

Be it known that I, WENDELL E. HERBST, a citizen of the United States, residing at Hartford, in the county of Hartford and State of Connecticut, have invented certain new and useful Improvements in Rubber Treads; and I do declare the following to be a full, clear, and exact description of the invention, such as will enable others skilled in the art to which it appertains to make and use the same.

This invention relates to improvements in rubber treads for attachment to foot wear to provide a cushioned tread and to prevent slipping, and particularly to certain improvements on the rubber heel shown in my United States Letters-Patent, No. 658,441, dated September 25, 1900.

The object of the present invention is to provide an elastic tread which obviates certain defects incident to my prior patented structure and which is simple, cheap and durable in construction and of maximum efficiency in use.

The invention consists of a rubber tread embodying certain novel features of construction and combination of parts, as will be hereinafter more fully described and particularly pointed out in the appended claims.

In the accompanying drawings,—Figure 1 is a top plan view of the improved heel; Fig. 2 is a bottom plan view thereof; Fig. 3 is a horizontal section through the heel; and Fig. 4 is a cross section.

In the construction shown in my prior patent, before referred to, the heel is provided with a metallic plate embedded therein and of horse-shoe form, the plate being substantially of the same width throughout its entire extent. This construction I find to be somewhat objectionable where the person using the heel runs the heel down on one side, as the metallic plate becomes exposed, rendering the heel unsightly. In my present structure this objection is obviated by providing the metallic plate on opposite sides of the center of its curved portion with recesses, which allow the heel to wear down without exposing the plate, thus increasing the life of the heel as well as obviating the objections referred to. In my

prior patent I also show the heel formed next the face intended for union with the boot or shoe with the peripheral extending lip or fin which projects beyond the side of the heel, said fin being adapted to bear against the heel at the edge and to provide a close union. This fin or lip, in practice, must be flattened out to the proper extent by the shoe maker when the heel is applied, which renders it somewhat troublesome in application. To obviate this objection I provide the heel in the present structure with an outwardly flaring surface which, when the heel is applied to the heel of the boot or shoe, exerts a wedging action against the end side of the boot or shoe heel and forms a close union therewith, thus preventing the entrance of dust, dirt, snow, etc. In my present structure I also make certain other improvements in the construction of the heel, all as will be hereinafter specifically described and pointed out in the appended claims.

Referring now more particularly to the drawings, the numeral 1 designates the rubber heel which has embedded therein a stiffening plate or strip 2 of metal; the said strip 2 corresponding in form to the outline of the heel, and provided with nail holes 3 registering with corresponding openings 4 in the tread surface of the heel. The rear curved portion of this plate is provided on the opposite sides of its center with notches or recesses 5 which come upon opposite sides of the center of the rear portion of the heel. These notches or recesses are for the purpose of permitting the heel to wear down at the rear on either side throughout the thickness of the heel without exposing the plate. By this means the wearer is not compelled to detach and throw away the heel when the plate becomes exposed, and as the plate remains concealed it cannot be broken or form a surface against which obstructions may catch.

The upper surface of the heel is formed with a frusto-conical countersink or recess 6 similar to that shown in my aforesaid patent and has, adjacent to its sides and rear edge, an upwardly and outwardly inclined or flared portion 7, said flared portion having a gradual inclination, sufficient enough to cause, when the heel is applied to the heel of

a boot or shoe, the outward expansion of such portion, adapting it to wedge tightly against the under side of the heel of the shoe and to thereby form a close union to prevent the entrance of dust, dirt and moisture. By this construction no prior flattening out of the part is required, as in my aforesaid patent, before applying the heel to the boot or shoe, while an equally advantageous result is secured. For the use of new boots and shoes, this outwardly inclined and flaring out portion, or rim 7, may be made, preferably, to extend and project out beyond the outer walls of the body of the rubber heel so as to permit the trimming-off even with the leather-heel portion without trimming the body of the rubber heel. The heel is also provided in its tread surface with a recess 8 of a frusto-conical form, which, in connection with the upper recess 6, lightens the heel so that a greater amount of material may be employed at the parts most subject to wear without making the heel unduly heavy. This recess also is adapted to prevent the heel from assuming a convex form as it wears, thus preventing slipping; and it also prevents clinging of snow to the heel, as the peculiar form of the walls of the recess causes the snow to be shed and pressed down upon the ground, instead of being retained. Furthermore, the recess by being of frusto-conical form, leaves a larger tread surface than any other form of recess, and this surface gradually increases instead of diminishing as the heel wears, insuring an effective resiliency action at all times. I may also utilize this recess as a receptacle for an anti-slipping material 9, which renders the heel more efficient for use in the country and in walking over rough surfaces. This anti-slipping fabric may consist of canvas or any other material suitable for the purpose.

In the drawings I have shown embedded with the metallic plate, a layer 10 of canvas or other like material, as it is more adhesive to rubber than to metal, therefore more binding to prevent the rubber heel from spreading over the leather portion and exerts a smooth union throughout the whole life of the rubber heel. Upright strips, of canvas or other suitable fabric, are embedded in the heel in the rear portion thereof, disposed longitudinally therein, radially with reference to each other and angularly with reference to the stiffening plate and extend from points within to points without the stiffening plate in planes which intersect the recessed portions thereof and extend nearly to the rear side of the heel. The lower edges of these fabric strips are exposed at the bottom of the heel and also at the rear side and bottom of the recess 8 therein. This longitudinal disposition of the fabric strips causes

them to wear evenly from end to end no matter how unevenly the rubber heel may wear and causes them to frictionally engage the pavement with maximum effect to increase their utility in preventing slipping, and their radial disposition on opposite sides of the longitudinal center of the heel disposes them in the line of the greatest wear whether the heel be "run down" on the inner or outer side. Furthermore, the angular disposition of the fabric strips with reference to the stiffening plate in the planes which intersect the recessed portions thereof and their rear extensions which extend to the rear of the said recessed portions, causes said fabric strips to reduce the wear of the heel at the parts thereof which are opposite the recessed weakened portions of the stiffening plate.

From the foregoing description, taken in connection with the accompanying drawings, the construction, mode of operation and advantages of the invention will be readily understood without requiring a more extended explanation.

Various changes in the form, proportion and minor details of construction may be made within the scope of the invention without departing from the spirit or sacrificing any of the advantages thereof.

Having thus described my invention what I desire to secure and claim by Letters-Patent, is:—

1. A rubber tread having an open-center metal stiffening plate embedded therein and provided with recesses in its rear side, and upright strips of anti-slipping fabric in the rear portion of the heel, embedded therein, disposed longitudinally thereof and radially with reference to each other, on opposite sides of the longitudinal center of the heel, and angularly with reference to the stiffening plate, said strips extending from points within to points without the stiffening plate in planes which intersect the recessed portions thereof, and also extending to and exposed at the lower surface of the rubber heel, substantially as described.

2. A rubber heel having strips of fabric embedded therein, disposed in an upright position and lengthwise thereof, and having their lower edges exposed at the bottom of the heel, substantially as described.

3. A rubber heel having strips of anti-slipping fabric embedded therein and disposed in an upright position and lengthwise thereof, and angularly with reference to each other, substantially as described.

4. A rubber heel having rearwardly diverging strips of anti-slipping fabric embedded therein, disposed in an upright position and longitudinally with respect to the heel, substantially as described.

5. A rubber tread having a recess in its

lower side and provided with strips of anti-slipping fabric embedded in the heel, disposed in an upright position and lengthwise thereof, said strips having their lower edges exposed at the bottom of the heel and at the rear side and bottom of the recess, substantially as described.

In testimony whereof I have hereunto set my hand in presence of two subscribing witnesses.

WENDELL E. HERBST.
